UNITED STATES PATENT OFFICE.

JAMES F. CRAVEN, OF PITTSBURGH, PENNSYLVANIA, ASSIGNOR TO CRAVEN ENGINEERING COMPANY, OF PITTSBURGH, PENNSYLVANIA, A CORPORATION OF PENNSYLVANIA.

CLOSURE FOR GREASE-GUNS.

1,036,967.

Specification of Letters Patent. Patented Aug. 27, 1912.

Application filed February 14, 1911. Serial No. 608,591.

To all whom it may concern:

Be it known that I, JAMES F. CRAVEN, a resident of Pittsburgh, in the county of Allegheny and State of Pennsylvania, have invented a new and useful Improvement in Closures for Grease-Guns, of which the following is a specification.

This invention relates to closures for receptacles for containing liquid, semi-liquid, 10 pasty or semi-solid substances, and more particularly to closures for oil cans, grease guns and the like, which are adapted or intended for discharging the contents of the receptacle through a spout or nozzle to oil or grease cups of machines and the like.

The object of the invention is to provide a closure for such receptacles so arranged that the act of attaching a removable spout to the receptacle operates the closure to open 20 the discharge orifice, while the act of detaching the spout operates the closure to close the discharge orifice.

The invention comprises the construction and arrangement of parts hereinafter described and claimed.

In the accompanying drawing Figure 1 is a vertical section through a grease gun having my invention applied thereto; Fig. 2 is a top view of the closure in closed position; 30 Fig. 3 is a sectional view showing a modification; and Fig. 4 is a section on the line 4-4, Fig. 3.

In the drawings the numeral 1 represents the body of a receptacle of any kind for containing a liquid, semi-liquid, pasty or semi-solid substance. It is represented as a can of general cylindrical form having the body formed of the tube 1, shown as made of paste or paper board, but which may be 40 made from sheet metal or other suitable material, having a bottom 2 and a head 3 of sheet metal suitably secured to the ends of the body in any suitable way, such as by crimping.

45 The head 3 is provided with a tubular extension or neck 4, whose end 5 is provided with the discharge orifice 6. Rotatably secured to the end 5 of the neck 4 is the closure 7 which is shown 50 in the form of a cap or inverted cup loosely fitting over the neck 4 and secured thereto by the rivet 8 or other means to keep it from separating from the sleeve but permitting it to rotate thereon. The cylind-

rical or side portion 9 of the cap is provided with external screw threads for receiving the correspondingly threaded inner end of the delivery spout 10 which will be of such length and shape as to deliver the substances to the grease or oil cups of machinery or like use.

The end of the cap 7 is provided with an opening 11 which in shape and size preferably corresponds to the opening 6 in the end of neck 4, and which is adapted to register with the opening 6 to permit the discharge of the material from the receptacle, or to be brought out of register with the opening 6 to close the discharge orifice. The cap 7 has a portion of the metal at the edge 70 of the opening 11 bent inwardly to form a tongue or projection 12 extending into the opening 6 and adapted to contact with the edges of the latter to limit the rotation of the cap 7 in both directions. Preferably the metal at one edge of the opening 6 is provided with a notch 13 to receive the projection 12 to insure the complete closing of the discharge orifice in one position of the cap 7.

The parts are so arranged that the mere act of screwing the spout 10 onto the cap 7, by the frictional engagement of the threads—at least at the end of the screwing down of the spout,—causes the cap 7 85 to rotate in the direction of the arrow, Fig. 2, to bring the openings 11 and 6 into register, while the mere act of unscrewing the spout causes the cap 7 to rotate in the opposite direction and cause the head of the cap 90 7 to cover the opening 6 and hence close the discharge orifice to prevent further material from escaping from the receptacle, or dirt to enter the same.

Figs. 3 and 4 illustrate a modification in which the spout 10 is threaded directly to the neck 4 of the receptacle and is provided with an inwardly extending tongue 14^a which engages the fluted or roughened periphery of the cap 7^a which is pivotally mounted on the end of said neck, as in Fig. 1. In this modification when the spout is being screwed onto the neck the tongue 14 engages with the periphery of the cap and rotates the latter to open the discharge orifice, 105 and at the beginning of the unscrewing operation the cap is rotated in the opposite direction to close the discharge orifice. The

tongue 14^a is preferably stamped out of the metal of the spout, although it may be a separate piece suitably secured thereto.

When the device is to be used for containing or discharging pasty or semi-solid substances, such as grease, suitable means is provided for forcing the same out of the receptacle. This means may be of various forms, and are represented by a piston or follower 10 17 provided with a cup leather 18 or the like yielding or expanding means for forming a close fit in the receptacle, and provided with a threaded opening 19 in which works a threaded rod or screw 20 by the rotation of which the piston is caused to move lengthwise in the receptacle to force the substance out of the same. The screw 20 is rotatably but endwise immovably secured to the body in any suitable manner, such as 15 20 by extending the same through the bottom 2, and providing the same with a shoulder or washer 22 on the inner side of the bottom, so that said screw can rotate but is endwise immovable. The outer end of the screw is 25 provided with a handle or key 23 with which to rotate said screw. It is obvious that when the screw 20 is rotated it causes the piston or follower 17 to move endwise in the receptacle and force the substance out of the 30 same. The piston or plunger is held against rotation by frictional contact with the walls thereof, or by other means, such as a longitudinal projection or rib 24 in the receptacle, which engages a notch in the periphery of 35 the piston or follower.

Various other means than those illustrated may be provided for forcing the substance out of the receptacle.

The device described is intended principally for lubricating purposes, where the receptacle must be stored between successive uses,—such as on automobiles,—or where it is desirable to remove the spout for storing the receptacle. The device is however 45 adapted to a variety of uses.

What I claim is:

1. A receptacle having a neck provided with a discharge orifice, a member movably mounted on the receptacle for closing the 50 discharge orifice, a removable delivery spout adapted to be placed over said neck and to be secured to the receptacle and so arranged that the act of securing the delivery spout moves said member in one direction on the receptacle to open the discharge orifice and the act of detaching the spout moves it in reverse direction to close the discharge orifice.

2. A receptacle provided with a discharge 60 orifice, a removable delivery spout therefor, a member for closing the discharge orifice mounted for limited movement on the outside of the receptacle, and a lost motion connection between the spout and closure constructed and arranged so that during the

act of attaching the delivery spout it moves said member to open the discharge orifice and also slips and moves relatively thereto until attached to the receptacle, and during the act of detaching the spout it moves said member to close the discharge orifice and also slips and moves relatively thereto until detached from the receptacle. 70

3. A receptacle provided with a discharge orifice, a removable delivery spout therefor, a closure for the discharge orifice connected to the receptacle to have limited rotative movement with relation thereto, and a connection between the delivery spout and closure so arranged that during the act of attaching the delivery spout it rotates said closure to open the discharge orifice and also moves with relation thereto until secured to the receptacle and during the act of detaching the spout it rotates said closure to 80 close the discharge orifice and also moves with relation thereto until detached. 85

4. A receptacle provided with a discharge orifice, a closure for said orifice connected to the receptacle and arranged to have limited rotative movement with relation thereto and endwise immovable thereon, and a removable delivery spout having threads for securing it to said receptacle, said spout being arranged to engage the closure and cause movement thereof and also rotate with reference thereto, whereby the attachment and detachment of the spout rotates the closure on the receptacle to respectively open and close the discharge orifice. 90 95

5. A receptacle provided with a discharge orifice, a closure for said orifice rotatably connected to the receptacle and endwise immovable thereon, and a removable delivery spout having a threaded connection at its 105 inner end for securing it to said receptacle and endwise movable thereon, said spout being arranged to frictionally engage the closure, whereby the attachment and detachment of the spout rotates the closure to 110 respectively open and close the discharge orifice, and stops to limit the rotation of the closure in both directions. 100

6. A receptacle provided with a discharge orifice, a closure rotatable and endwise immovable on said receptacle and provided with threads, and a delivery spout threaded to engage said closure, whereby the attachment and detachment of the spout rotates the closure to respectively open and close 115 120 the discharge orifice. 120

7. A receptacle provided with a neck having a discharge orifice, a closure movably mounted on the outside of the neck, a removable delivery spout constructed for attachment to said receptacle and adapted to surround said neck and arranged upon attachment to or detachment from said receptacle to frictionally engage and move the closure to open and close the orifice, said 125 130

spout being rotatably movable with relation to the closure.

8. A receptacle provided with a neck having a discharge orifice, a closure rotatably mounted on and surrounding the neck, a removable delivery spout constructed for attachment to said closure and arranged upon attachment to or detachment therefrom to frictionally engage and rotate the same to 10 open and close the orifice, the spout being rotatably movable with relation to the closure, and stops for limiting movement of the closure in either direction.

9. A receptacle provided with a discharge orifice, a closure rotatable on said receptacle and provided with threads, and a delivery spout threaded to engage said closure, whereby the attachment and detachment of the spout rotates the closure to respectively open 20 and close the discharge orifice, and stops to limit the rotation of the closure in both directions.

10. A receptacle provided with a discharge orifice, a cap rotatable on said receptacle and provided with an opening adapted to register with the discharge orifice and being provided with threads, and a delivery spout provided with corresponding threads, whereby the attachment and detachment of the spout to the cap rotates the latter to bring the opening in the cap respectively into and out of register with the discharge orifice. 25

11. A receptacle provided with a discharge orifice, a cap rotatable on said receptacle and provided with an opening adapted to register with the discharge orifice and being provided with threads, a delivery spout provided with corresponding threads, whereby the attachment and detachment of the spout to the cap rotates the latter to bring the opening in the cap respectively into and out of register with the discharge orifice, and stops to limit the rotation of the cap in both directions. 30

12. A receptacle provided with a neck having a discharge orifice, a closure rotatable on said receptacle and provided with an opening adapted to register with the discharge orifice, and a delivery spout surrounding said neck and having a threaded connection for securing it to the receptacle and arranged to engage said closure, whereby the attachment and detachment of the spout rotates the closure to bring the opening therein respectively into and out of register with the discharge orifice, and a projection on one of the parts extending into the opening in the other for limiting the rotation of the closure in both directions. 35

In testimony whereof, I have hereunto set my hand.

JAMES F. CRAVEN.
